UNITED STATES PATENT OFFICE.

RICHARD D. REED, OF WESTFIELD, MASSACHUSETTS, ASSIGNOR TO THE H. B. SMITH COMPANY, OF WESTFIELD, MASSACHUSETTS, A CORPORATION OF MASSACHUSETTS.

BOILER.

1,334,676.

Specification of Letters Patent. Patented Mar. 23, 1920.

Application filed February 24, 1915. Serial No. 10,197.

To all whom it may concern:

Be it known that I, RICHARD D. REED, a citizen of the United States, and a resident of Westfield, county of Hampden, State of 5 Massachusetts, have invented certain new and useful Improvements in Boilers, of which the following is a specification.

This invention relates particularly to sectional boilers, and is designed to provide 10 means to permit the burning of soft coal and effect complete combustion in order to eliminate the issuance of smoke.

In the drawings—

Figure 1 is a central longitudinal section 15 of a boiler embodying my invention.

Fig. 2 is a front view, with the front portion of the boiler removed.

Fig. 3 is a horizontal section on the line 3—3 of Fig. 2.

20 In carrying out my invention I provide in conjunction with a sectional boiler, a chamber for mixing and igniting the gases and volatile matter, and a second chamber within which the combustion may be completed. These chambers are built into and 25 as a part of a sectional cast iron boiler, and are formed by water sections and separated by water-carrying partition walls so that the heat of the burning matter may be utilized 30 for the performance of useful work. Each partition wall has an elongated flue through it, and these flues are angularly disposed relatively to one another, thus causing the gases and volatile matter to 35 change the direction of travel during passage from the fire box to the stack, insuring that the hot gases will be mixed and brought into contact with the volatile matter and ignited. The sections which form 40 the walls of the mixing and combustion chambers are similar to the sections forming the fire box of the boiler, and they may be assembled together in the same way. In some cases it may be convenient to make 45 the flue sections or partition walls so that their position may be interchangeable with the other sections, in order to vary the size of either of the chambers to meet existing conditions.

50 Another feature of construction is to be found in the division plate located in the ash pit and dividing the grate into separate draft areas, which permits of coking a charge of coal on one side of the grate while 55 the other side is burning bright.

In the drawings, *a* denotes the grate divided longitudinally by the partition *b*, and each part provided with the usual draft doors or openings controlled by shutters. *c* denotes the fire box section, built up from 60 any desired number of water sections *d*. *e* is a flue section or partition wall, which forms the rear wall of the fire box section and is provided with a longitudinal flue 5. 10 denotes the mixing chamber located 65 directly back of the fire box and connected therewith by the flue 5. It is built up of any desired number of water sections *d'*, similar to those forming the fire box. As shown, there is one of these sections, and 70 then comes the second flue section or partition wall, 15, forming the end of the mixing chamber and having a vertical flue 20. Back of this second flue section is the combustion chamber 25, formed by the desired 75 or proper number of water sections *d''*, three of such sections and a back section *d'''* being shown.

The complete boiler thus comprises two 80 end compartments and an intermediate compartment, connected by the flues 5, 20, which are angularly disposed with relation to one another. And it is this angular arrangement of the flues which causes the gases to whirl 85 in the intermediate chamber and thus become thoroughly mixed and ignited, with the result that they are completely burned up in the combustion chamber.

By forming the boiler sectionally, any size 90 of fire box, mixing chamber, or combustion chamber, can be provided to meet any requirement. By this arrangement a two-fold advantage is secured, namely, the consumption of the smoke, and the increased capacity of the boiler. For convenience of 95 reference, the water sections making up the fire box proper of the boiler may be considered as the main series of sections, and those sections making up the mixing and combustion chambers may be considered 100 as the secondary series of sections.

I claim as my invention:

1. In a combined boiler and furnace the combination with a series of abutting hollow water sections, of a fire box, a combustion 105 chamber and a mixing chamber between said fire box and combustion chamber, a wall forming a partition between said fire box and mixing chamber and provided with a horizontally extending comparatively nar- 110

row flue opening, and a second wall forming a partition between said mixing chamber and combustion chamber and provided with a vertically extending comparatively narrow flue opening, said water sections being of such size and so constructed as to be interchangeable to thereby vary the relative sizes of the mixing chamber and the combustion chamber to adapt them to burning different qualities of soft coal, both of said partitions being hollow water carrying walls formed integral with said sections.

2. In a combined boiler and furnace the combination with a series of abutting hollow water sections, of a fire box, a combustion chamber and a mixing chamber between said fire box and combustion chamber, a wall forming a partition between said fire box

and mixing chamber and provided with a horizontally extending comparatively narrow flue opening, and a second wall forming a partition between said mixing chamber and combustion chamber and provided with a vertically extending comparatively narrow flue opening, said water sections being of such size and so constructed as to be interchangeable to thereby vary the relative sizes of the mixing chamber and the combustion chamber to adapt them to burning different qualities of soft coal, one of said partitions being a hollow water carrying wall formed integral with one of said sections.

RICHARD D. REED.
